(57) CLAIM

The ornamental design for an eyelash case, as shown and described.

DESCRIPTION

FIG. 1 is a side elevation view of an eyelash case showing my design;

FIG. 2 is a perspective view thereof;

FIG. 3 is a bottom plan view thereof; and,

FIG. 4 is a top plan view thereof.

The broken lines in the drawings depict parts of the eyelash case that form no part of the claimed design.
